UNITED STATES PATENT OFFICE.

JOHN EMORY RYLANDER, OF AMERICUS, GEORGIA.

DESIGN FOR A RACK.

54,183.

Specification for Design.

Patented Nov. 11, 1919.

Application filed July 12, 1917. Serial No. 180,229. Term of patent 7 years.

To all whom it may concern:

Be it known that I, JOHN EMORY RYLANDER, a citizen of the United States, residing at Americus, in the county of Sumter and State of Georgia, have invented a new, original, and ornamental Design for a Rack, of which the following is a specification, reference being had to the accompanying drawing, forming part thereof.

The figure is a perspective view of a rack, showing my new design.

I claim:

The ornamental design for a rack as shown.

JOHN EMORY RYLANDER.

Copies of this patent may be obtained for five cents each, by addressing the "Commissioner of Patents, Washington, D. C."
